tion of Delaware

Original application June 14, 1939, Serial No.
279,045. Divided and this application July
19, 1941, Serial No. 403,150

3 Claims. (Cl. 80—60)

This invention relates to the rolling of steel strips and sheets, and the application herein is a division of my application Serial No. 279,045, filed June 14, 1939, now Patent No. 2,271,459, for an improvement in a Rolling mill.

It is the object of my invention by rolling steel strip and sheet to produce deep-drawing stock in which the "deadening" effect has been carried to such stage that there is little or no tendency toward structural rearrangement in the stock, and no substantial loss of its deep-drawing properties during relatively long periods of time intervening between the deadening treatment and the deep-drawing operation.

In cold-rolling strip and sheet steel to the condition of a deep-drawing stock, it has been customary to effect the final reduction, after an annealing operation, in what is known as a "temper pass" under relatively severe pressure and tension. This final rolling results in such structural change in the stock as to adapt it for use as deep-drawing stock. That is, its ultimate yield point is raised and its elastic limit is lowered, permitting the stock to endure without loss of cohesion severe deformation into shapes which it permanently retains. There has been the difficulty that the deep-drawing property of the stock has not been persistent, but that in a relatively short time following a "deadening" operation there will occur such structural rearrangement in the stock that it is not suitable for its intended use, without having more work done on it.

It is, however, a fact that if the stock in temper working be worked with great violence, there is a very great increase in the persistence of deep-drawing properties in the stock. Such persistence in deep-drawing properties may be created by hammering, which is, however, a commercially impractical operation for the purpose. I have appreciated that if strip and sheet steel be rolled at abnormally high speed, and under abnormally high pressure, that is, at a speed and under a pressure not previously attempted in the art, persistent deep-drawing qualities might be obtained. That is, the order of violence in working which is obtainable by heavy hammer blows must be approached in rolling in order commercially to obtain a persistence in deep-drawing properties analogous to that attainable under a hammer.

It is to be understood that the word "violence" as I above use the term, is descriptive of time-qualified reduction in the stock, or otherwise expressed, it is descriptive of a measure of reduction in the stock as one component and the rate at which the reduction is effected as another com-

ponent. I have found in rolling, and the analogy to hammer action is here yet pertinent, that the greater the violence with which the reduction is effected, the more persistent will be the deep-drawing qualities of the stock. When the working (i. e., the violence of reduction) is increased well beyond that effected in normal practice, the results are striking. For example, by subjecting the stock to a temper-rolling at a rolling pressure of 200,000 pounds per linear inch of work roll face and at a speed of 2500 ft. of the stock per minute through the work rolls, the deep-drawing properties of the stock persist for many times the persistence period of stock rolled under the conditions previously employed commercially. Also the proportional permanent retention of deep-drawing properties is far greater than has been obtained in previous commercial practice.

In obtaining this violence in working the stock, I utilize a rolling instrumentality capable of withstanding "abnormally" high pressures, of operating at "abnormally" high speeds, and of working the stock at "abnormal" speed and under "abnormal" pressure. In speaking of "abnormal" loads, and "abnormal" speed, it may be stated that loads of as much as 150,000 pounds per linear inch have been considered to be higher than normal in temper mills, and it has not been previously attempted to operate temper mills under so high a load. Also travel of the strip or sheet steel through temper mills has not previously been attempted at a speed as high as 1500 feet per minute.

As illustrative of instrumentalities capable of performing the method of my invention, I may use a rolling mill which includes the novel roll organization disclosed and claimed in my co-pending application Serial No. 279,045, filed June 14, 1939, to which reference has been above made. The accompanying drawings show an embodiment of such exemplary apparatus, as follows:

Fig. I is a diagrammatic elevation of a set, or stand, of rolls together with backing structures organized with the rolls.

Fig. II is a view of a rolling mill assembly, partly in front elevation and partly in vertical section, showing a mounted arrangement of the rolls and backing structures shown in Fig. I together with means for ultimately receiving and reacting to the pressures of rolling.

Fig. III is a side elevational view of the rolling mill shown in Fig. II.

Fig. IV is a front elevational view of a set, or stand, of rolls and their associated backing structures similar to Fig. I in its general arrangement.

but showing modification in the arrangement of the rolls and backing structures.

In Fig. I there is shown a stand of two work rolls 1 and 2 against the faces of which bear respectively the faces of the back-up rolls 3 and 4. Upon the back-up rolls 3 and 4, and laterally beyond the contact faces of these rolls, are pairs of wheels 5 and 6. The wheels 5 contact back-up roll 3 on both sides of the median portion in which it is in contact with the face of work roll 1, and the wheels 6 similarly contact the back-up roll 4. The pairs of wheels 5 and 6 are carried respectively on relatively heavy shafts 7 and 8, so that the backing structures have a general spool shape. For reasons which will appear, the wheels should preferably be made integral with, or otherwise be fixed to, their carrying shafts.

By consideration of Fig. I, it will be seen that the spool-form backing members relieve the necks of the back-up rolls, and their associated bearings, from the rolling pressure sustained by the back-up rolls. These backing members have in the assembly the specialized function of receiving and enduring the high stresses incidental to the rolling pressure, and they are, therefore, specifically adapted to that purpose. Thus the shafts 7 and 8 may be designed for great strength, and a high factor of safety may be provided both in the shafts and in their associated bearings.

The structural arrangement of the spool-shaped backing members tends to distribute reaction to the rolling pressure symmetrically along the beam formed by the shafts and wheels, and provides both end and intermediate bearing spaces of relatively great length, both outwardly of, and between, the wheels. In the assembly shown in which the bearings and screwdowns are symmetrically located, and equidistant with respect to the pressure transmitting wheels on shafts 7 and 8, the arrangement will tend to balance the rolling pressures on the mill, by tending strongly to centralize reaction to those pressures. In Fig. I of the drawings there is indicated the relative loads on the wheels and shafts forming the ultimate backing structures, when the rolling pressure is uniform throughout the entire width of the stock being rolled. An inherent characteristic of the backing structure is that it tends, in accordance with the principle of a continuous beam, to centralize reaction to the rolling pressure of the mill. It thus functions also to decrease inequality in reaction to non-uniformly distributed rolling pressure, by its tendency to resolve the reaction toward a central line.

The value of thus centralizing reaction to rolling pressures is most striking when considered in connection with the conditions which exist in the use of a conventional 4-high mill. In such practice there are usually changing and highly unbalanced loads on the opposite necks of each of the back-up rolls, resulting from the reaction of those rolls to the rolling pressures in the mill.

As shown in Fig. I of the drawings, the back-up rolls 3 and 4 are shouldered to provide respectively in the two back-up rolls peripheral surfaces 9 and 10, against which the pairs of wheels 5 and 6 respectively bear. There is substantial advantage in such a structure of the back-up rolls, in that it provides a progressive decrease in angular velocity from the work rolls upwardly and downwardly of the roll stand to the shafts 7 and 8. Thus, the work rolls, being of lesser diameter than the back-up rolls, the back-up rolls will be driven less rapidly than the work rolls, and the back-up rolls being formed, as shown, with a

diameter less than that of the wheels which they contact, there is a further drop in angular velocity from the back-up rolls to the shafts 7 and 8. This decreased angular velocity simplifies the bearing problems for the pressure-receiving spools.

Whereas it is desirable that the wheels of each backing structure be fixed on a rotatable shaft; the wheels may be rotatably mounted on a fixed shaft, without sacrificing the principle of pressure centralization, and the relief given the roll necks.

In Figs. II and III of the drawings there is illustrated mounting structure for the roll assembly of Fig. I. The mounting structure shown is preponderantly conventional in its form and arrangement, and comprises roll housings 11 supported by shoes 12 and having therein windows 13. The work rolls 1 and 2 have their necks extended respectively into chocks 14 and 15, and the back-up rolls 3 and 4 have their necks extended respectively into chocks 16 and 17. The necks of the upper spool are carried by chocks 18, each of which is shown as provided with sleeve bearings 19 surrounding the necks of the spools, and the necks of the lower spool are carried by blocks 20 equipped with sleeve bearings 21. Balancing springs 22, 23 and 24, arranged in sets, serve to maintain the rolls in operative contact with each other and with the adjusting means of the assembly. Desirably in large installations, these springs are replaced, in accordance with common practice, by fluid pressure cylinders or counterweights.

The mounting assembly, thus described, is of conventional form and arrangement. There are, however, a chock 25 and a block 26 having respectively sleeve bearings 27 and 28, which are adapted intermediately to support the shaft 7 of the upper spool and the shaft 8 of the lower spool. The bearing block 26 is held against horizontal displacement by a beam structure 33, which is supported on the mill shoes 12, and the chock 25 for the upper spool is held against horizontal displacement by means of webs 29 extended from the roll housings 11 at the edges of the windows therein. Screwdowns 30 and 31 bear against the chocks 18, and a third screwdown 32 bears against the chock 25. It is to be understood that power to drive the mill may be directly applied to the work rolls, to the back-up rolls, or to the spools, in the conventional manner, by a suitable pinion stand and drive operating through driving spindles.

Fig. IV of the drawings illustrates a modified arrangement in which the backing rolls are not shouldered. In this modification the wheels 5a and 6a have contact with the faces of the unshouldered back-up rolls 3a and 4a in zones 3b and 4b which lie outwardly of the working faces of the work rolls 1a and 2a, so that the spool has similarly the effect of straddling the ultimate working faces of the rolls.

Since I obtain my desirable effect of imparting persistent deep-drawing properties to steel strip and sheets by violent working, it is important that not only the pressure under which the stock is rolled and the speed of its travel be high, but it is also important that the reduction in the gauge of the stock in a single passage through the rolls be relatively great. If the size of the work rolls were to be so increased as greatly to decrease the angle at which the work rolls bite into the stock, the effective rolling pressure would be decreased by slippage, and the utility of exerting great

pressure through the screwdowns of the rolling mill assembly would in large measure at least be lost. This necessitates the employment of work rolls providing a relatively great bite angle with the stock. In previous practice in 40" to 42" temper mills, work rolls have been used which have a diameter of from about 16" to 30", in accordance with the gauge and composition of the stock subjected to treatment. In smaller mills the diameter of the work rolls is proportionally less. In conducting my method I use work rolls which are at least no greater in diameter than those commonly used in temper mills of equal size and for operation on stock of like gauge and composition. This is in order that increased speed and pressure will not be offset by work rolls so large as to provide a relatively low bite angle and thereby to minimize the reduction in the stock caused by a single passage of the stock through the rolls.

I prefer to use rolls the diameter of which is small as compared with the diameter of work rolls in temper mills of like size used in like operations. Thus in 40" to 42" temper mills, I prefer in conducting my method to use work rolls down to 10" diameter and even less, and in small mills correspondingly to use work rolls of lesser diameter. In temper mills larger than 40" to 42" mills the diameter of the work rolls will be correspondingly greater, but in any case I use work rolls having a diameter no greater than those commonly used in temper mills of like size and on like work, and prefer to use work rolls which are relatively small with respect to the common practice of the art. I have found that if the backing for the work rolls be of very high value, as is the case in the exemplary apparatus described above, I am able to use work rolls of very small diameter to apply abnormally high pressures.

Utilizing work rolls of adequately limited diameter I thus retain or increase the effect of violence caused by the high pressure and high speed at which I roll the stock. As exemplary of procedure in accordance with my invention, I may give an operation upon cold coiled strip of about 16 gauge and 34" width of a composition generally accepted as giving full deep-drawing properties, such as 0.06 to 0.10 carbon steel having no substantial content of alloying metals, normalized. Having used the screwdowns to establish a pass, and to exert a pressure in the neighborhood of 200,000 pounds per linear inch on the stock, I pass the stock through the work rolls at a speed between 2,000 ft. per minute and 2,500 ft. per minute. The work rolls are of about 14" diameter and the reduction in the stock is about 30%. No tensioning means tending to pull the stock through the temper mill is used. Such sheets show no substantial decrease in their deep-drawing properties even when relatively long

periods of time intervene between the temper-rolling and the deep-drawing operation.

I have shown herein as illustrative of an instrumentality usable in effecting my purpose, a rolling mill organization capable of sustaining abnormally high pressure without making the structure of the apparatus of abnormally great size. It is to be understood, however, that insofar as concerns my method herein disclosed, such method may be performed by using back-up rolls of abnormally great size in the temper mill or by otherwise so organizing the temper mill that it is capable of applying and sustaining abnormally great rolling pressures and operating at abnormally high speeds.

I claim as my invention:

1. The herein-described method of making from steel strip and sheet a cold-rolled product having persistent deep-drawing properties by cold-rolling a normalized steel strip or sheet of deep-drawing composition under a rolling pressure approximately as great as 200,000 pounds per linear inch of roll contact with the stock at a speed approximately as great as 2,000 feet per minute in work rolls of a diameter so small as to give a bite angle at least as great as that conventional in temper mill practice; by the abnormally severe working thus effected so "deadening" the stock as substantially to eliminate tendency toward structural rearrangement therein.

2. The herein-described method of making from steel strip and sheet a cold-rolled product having persistent deep-drawing properties by cold-rolling a normalized steel strip or sheet of deep-drawing composition under a rolling pressure within the approximate range of 150,000 pounds per linear inch of roll contact with the stock to 200,000 pounds per linear inch of roll contact with the stock at a speed of from about 1,500 feet per minute to about 2,500 feet per minute in work rolls of a diameter so small as to give a bite angle at least as great as that conventional in temper mill practice; by the abnormally severe working thus effected so "deadening" the stock as substantially to eliminate tendency toward structural rearrangement therein.

3. The herein-described method of making from steel strip and sheet a cold-rolled product having persistent deep-drawing properties by cold-rolling a normalized steel strip or sheet of deep-drawing composition under a rolling pressure in excess of 150,000 pounds per linear inch of roll contact with the stock at a speed in excess of 1,500 feet per minute in work rolls of a diameter so small as to give a bite angle at least as great as that conventional in temper mill practice; by the abnormally severe working thus effected so "deadening" the stock as substantially to eliminate tendency toward structural rearrangement therein.

WILLIAM M. McCONNELL.
